HORACE W. KING, OF ANN ARBOR, MICHIGAN, ASSIGNOR TO KING-SEELEY CORPORATION, OF ANN ARBOR, MICHIGAN, A CORPORATION OF MICHIGAN

LIQUID DEPTH INDICATING DEVICE

Application filed March 11, 1925. Serial No. 14,715.

This invention relates to liquid depth indicating devices and more particularly to liquid depth indicating devices of that type having an air chamber in communication with the liquid being measured and also with a pressure gage. One of the objects of the invention is the provision of means dependent upon the motion of the liquid being measured for effectively replenishing the air chamber with air. Another object is the provision of air replenishing means which is dependent for operation upon the undulation or rising and falling of the surface of the liquid being measured.

15 Further objects of the invention reside in the novel features of construction and combinations and arrangements of parts as more fully hereinafter set forth.

In the drawings:

20 Figure 1 is a perspective view of a liquid depth indicating device embodying my invention;

Figure 2 is an elevation thereof at right angles to Figure 1 and shown partly in section;

25 Figure 3 is a cross section on the line 3—3 of Figure 2;

Figure 4 is a cross section on the line 4—4 of Figure 3;

30 Figure 5 is a sectional elevation of a modified liquid depth indicating device;

Figure 6 is a side elevation of a portion thereof;

Figure 7 is a bottom plan view thereof;

35 Figure 8 is a perspective view of another modified liquid depth indicating device;

Figure 9 is an elevation thereof partly in section;

40 Figure 10 is a cross section on the line 10—10 of Figure 9.

As shown in the present instance my liquid depth indicating device is applied to the supply tank 1 of a motor vehicle having the air vent 2 and the opening 3 in its top. This latter opening is in the present instance sur-

rounded by the annular flange 4 having external threads which are engaged by the flanged nut 5.

6 is the air chamber of the liquid depth indicating device and 7 the feeding chamber 50 located below the air chamber and communicating therewith through the restricted opening 8. These chambers are formed by the bell 9 having an open lower end above and preferably adjacent to the bottom of the supply tank and the transverse partition wall 10 between the top and lower end of the bell. The restricted opening 8 is in the partition wall. 11 is a fine meshed screen extending across the open lower end of the bell 9 for straining the liquid fuel as it passes into the feeding chamber. 12 is a pressure tube extending air tight through the top of the bell 9 and having an open lower end communicating with the upper portion of the air chamber. This tube extends through and is secured to the plate 13 which is clamped between the upper end of the annular flange 4 and the annular flange of the nut 5, and the upper end of this tube is suitably detachably connected to the tube 14 which leads to the pressure gage 15 located upon the dash of the motor vehicle. 16 is a suction tube extending through and secured to the plate 13 and extending air tight through the top of the bell 9 and the partition wall 10, and having an open lower end terminating within the lower portion of the feeding chamber 7. This tube is detachably connected to a suitable device for withdrawing the liquid fuel such as a pump, vacuum tank or the like, by suitable means including the tube 17. 18 is the pressure relief tube extending through and secured to the plate 13 and extending air tight through the top of the bell 9 and having an open lower end terminating within the recess 19 which latter is formed by depressing a portion of the partition wall 10. The upper end portion of this 90

pressure relief tube is curved downwardly and terminates in an open end in communication with the air outside the supply tank.

To accurately indicate the depth or quantity of liquid fuel in the supply tank it is essential that the level of the liquid fuel in the bell 9 be at a predetermined height. This is accomplished in the present instance by placing the air chamber 6 in communication 10 with the liquid fuel through the restricted opening 20 in the side wall of the bell and above the partition wall, and also by replenishing the bell with air. As shown 21, 22, 23 and 24 are reservoirs located at different 15 heights above the air chamber 6 and within the supply tank and communicating with the lower portion of the feeding chamber 7 through the tubes 25, 26, 27 and 28 respectively which pass air tight through the top of the bell 9 and the partition wall 10 and have open lower ends terminating in substantially the same plane, and normally sealed by the liquid fuel. The reservoirs have open upper 20 ends for alternately receiving air and the liquid fuel during the undulation or rising and falling of the surface of the latter caused by the movement of the motor vehicle. For trapping air I have provided in each reservoir 25 an inverted cup 29 preferably secured to a side of a tube leading upwardly through the base of the reservoir and having its top spaced above and its side wall terminating below the open upper end of this tube. Each reservoir has a capacity greater than the 30 combined capacities of the inverted cup therewithin and the tube leading therefrom to the feeding chamber.

In operation and assuming the liquid depth indicating device to be in the supply tank and 40 the latter to be empty, liquid fuel when poured into the supply tank passes upwardly through the screen 11 into the feeding chamber 7 and the various tubes having open upper ends and also through the restricted opening 45 20 into air chamber 6 until the pressure of air in this air chamber counterbalances the hydrostatic pressure of the liquid fuel in the supply tank. The pressure within this air chamber is communicated to the gage 15 50 through the tubes 12 and 14. The liquid fuel is drawn from the supply tank through the screen 11 and tubes 16 and 17 to the liquid fuel withdrawing device from which it may be fed to the carburetor in the usual manner.

During the travel of the motor vehicle the surface of the liquid fuel in the supply tank undulates or rises and falls so that one of the reservoirs is alternately exposed to the air and filled with the liquid fuel. When the liquid 60 fuel fills the reservoir and the surface of the liquid fuel temporarily lowers again at the location of the reservoir, the liquid fuel in this reservoir will pass downwardly and into the tube connected to the reservoir a corresponding distance and in doing so this liquid

fuel will carry the air trapped in the inverted cup of the reservoir downwardly through the tube and into the feeding chamber. This air which has been carried into the feeding chamber is then free to pass upwardly through the restricted opening 8 into the air chamber 6 to displace any liquid fuel therewithin down to the level of the restricted opening 20 after which any surplus air will escape through this restricted opening. When the liquid fuel starts flowing from a reservoir to the feeding chamber it will continue flowing under a siphoning action until the lower end of the inverted cup in that reservoir is uncovered and air again fills the inverted cup.

The lower end of the pressure relief tube 18 is sealed by liquid fuel located in the recess 19 so that under normal operating conditions no air enters the air chamber through the pressure relief tube. However, if either an abnormal suction or an abnormal pressure is created in the air chamber, the pressure relief tube serves as a passageway for air either to or from the air chamber, so that the indicating liquid in the gage will neither be withdrawn or forced therefrom.

The opening 3 in the supply tank has a diameter greater than that of the bell 9 and also the distances between the furthermost side wall of the oppositely positioned reservoirs whereby the device may be readily inserted into the supply tank or removed therefrom. These reservoirs are preferably secured to the tubes 12, 16, 18 and 28 to form a substantial unit therewith.

In the modified construction shown in Figures 5, 6 and 7 the bell 30 has extending thereacross above its lower end the partition wall 31 having the restricted opening 32 therein and the depression 33 forming the recess 34, into which extends the lower open end of the pressure relief tube 35. A suitable cup shaped fine meshed screen 36 is secured to the bell 30 and the partition wall 37 which latter depends from the partition wall 31 and extends between the opposite sides of the bell. The tubes 38, 39, 40 and 41 which are connected to the reservoirs 42, 43, 44 and 45 respectively located at different distances above the bell 30 open into the feeding chamber 46, which is formed below the partition wall 31 and enclosed by the side wall of the bell below this partition wall and the wall 37 as well as the screen 36, the openings being in the lower ends of these tubes and below the partition wall 31. 47 is the suction tube which is detachably connected to the vacuum tank or other suitable source of vacuum and is soldered to the side of the bell 30 and has preferably a lower plugged end 48 and a lateral opening 49, which is located below the partition wall 31 and registering with the space or chamber formed by the partition wall 31, the wall 37, the screen 36 and the

side wall of the bell 30 between the partition wall and the screen.

In operation the liquid fuel is drawn into the suction tube 47 independently of either the feeding chamber 46 or the air chamber 50 thereabove and enclosed by the bell 30 and the partition wall 31. This liquid fuel, however, is strained by the screen 36. The operation of the reservoirs and the tubes connected thereto, as well as the inverted cups secured to the upper ends of the tubes and located in the reservoirs is the same as that previously described in that air is introduced intermittently to the feeding chamber below the air chamber to maintain a predetermined level of liquid fuel in the bell, which in this construction is determined by the lower end of the bell 30.

In the modified liquid depth indicating device illustrated in Figures 8, 9 and 10 the general arrangement of parts of the liquid depth indicating device illustrated in Figures 1 to 4, inclusive, is the same. In detail 51 and 52 are respectively the air chamber 25 and feeding chamber formed by the bell 53 and the transverse partition wall 54 located between the top and lower end of the bell. The feeding chamber is located below the air chamber and communicates therewith 30 through the restricted opening 55. The air chamber communicates with the liquid fuel in the supply tank through the restricted opening 56 located above the transverse partition wall. 57 is a fine meshed screen extending 35 across the lower end of the bell for straining the liquid fuel as it passes into the feeding chamber. 58 is a pressure tube extending air tight through the top of the bell 53 and having an open lower end communicating with the upper portion of the air chamber and an upper end communicating with a suitable pressure gage, which is preferably located upon the dash of the motor vehicle. 59 is a suction tube extending longitudinally and at 40 45 the side of the bell 53 and below the lower end of this bell, the lower end of the tube being closed by a suitable means such as the plug 60. The bell is preferably provided with a longitudinally extending concavity or groove 50 55 61 for receiving the suction tube, this concavity or groove being formed in any suitable manner as by means of suitable dies used in drawing the bell. The suction tube is secured by and suitable means to the bell, there being no necessity of making the joint between the side wall of the bell and the suction tube air tight. 62 is an opening in the suction tube 59 above the plug 60 and registering with the opening 63 in the side wall of the bell 60 below the transverse partition wall 54. This suction tube is suitably connected to a suitable liquid fuel withdrawing device. 64 is a pressure relief tube extending air tight through the top of the bell 53 and having an 65 open lower end terminating within the recess

65 formed by depressing a portion of the transverse partition wall 54. The upper end portion of this pressure relief tube is preferably curved downwardly above the plate 66 and terminates in an open end in communication with the air outside the supply tank. Both the pressure tube 58 and the suction tube 59, as well as the pressure relief tube 64 are preferably fixedly secured to the plate.

67, 68, 69 and 70 are reservoirs located at 70 different heights above the air chamber 51 and within the supply tank and communicating with the lower portion of the feeding chamber through the tubes 71, 72, 73 and 74, respectively, which as shown, pass air tight through the bell 53 and the transverse partition wall 54. The reservoirs have open upper ends for alternately receiving air and the liquid fuel during the undulation or rising and falling of the surface thereof caused by the movement of the motor vehicle. Each of the reservoirs is preferably provided with the longitudinally extending concavity or groove 75 for receiving the suction tube 59. The tubes 71, 72, 73 and 74 extend air tight through the bottoms of the reservoirs and each tube terminates in an open upper end located above the bottom of its respective reservoir and enclosed by the inverted cup 76 for trapping air.

The operation of this liquid depth indicating device is the same as that illustrated in Figures 1 to 4 inclusive, but the arrangement is such that comparatively shallow reservoirs may be used inasmuch as their diameters are substantially equal to the diameter of the bell 53 so that their heights may be decreased and still provide individual capacities greater than the combined capacities of the inverted cup respectively located there within 100 and the tube leading from this inverted cup to the feeding chamber.

What I claim as my invention is:

1. In a liquid depth indicating device, the combination with an air chamber provided with means for placing said chamber in communication with a liquid having an undulatory surface and a gage, means for placing said gage in communication with said air chamber, of means for introducing air into said air chamber including a reservoir for alternately receiving air and the liquid during the undulation of the liquid surface, and means forming a passageway for air and the liquid extending between said reservoir and air chamber including an air trap above the bottom of said reservoir for receiving air and the liquid from said reservoir.

2. In a liquid depth indicating device, the combination with an air chamber provided with means for placing said chamber in communication with a liquid having an undulatory surface, and a gage, means for placing said gage in communication with said air chamber, of means for introducing air into

- 5 said air chamber including a reservoir for alternately receiving air and the liquid during the undulation of the liquid surface, and means forming a passageway from said reservoir to said air chamber having an upper end portion with a solid top and downwardly extending portions, with one of said downwardly extending portions provided with an opening into said reservoir.
- 10 3. In a liquid depth indicating device, the combination with an air chamber provided with means for placing said chamber in communication with a liquid having a rising and falling surface, and a gage, means for placing 15 said gage in communication with said air chamber, of means for introducing air into said air chamber including reservoirs spaced at different distances above said air chamber and having openings whereby said reservoirs may alternately receive air and liquid during the rising and falling of the liquid surface, and means forming passageways for 20 air and the liquid extending between said reservoirs and air chamber, each passageway-forming means having its lower end normally sealed by the liquid and including an air trap at the upper end of the respective passageway for directly receiving air and liquid from the respective reservoir.
- 25 4. In a liquid depth indicating device, the combination with an air chamber provided with means for placing said chamber in communication with a liquid having an undulatory surface, and a gage, means for placing said gage in communication with said air chamber, of means for introducing air in said air chamber including a reservoir for alternately receiving air and the liquid during the undulation of the liquid 30 surface, a tube extending through the bottom of said reservoir and communicating with said air chamber, and an inverted cup extending within said reservoir and surrounding the upper end of said tube and having its top spaced thereabove.
- 35 5. In a liquid depth indicating device, the combination with an air chamber having its lower end submerged in the liquid to be measured and the surface of which liquid is subject to movement, and a gauge and means connecting said gauge and air chamber, of 40 means for introducing air into said air chamber including reservoirs spaced at different distances above said air chamber and having openings whereby said reservoirs may alternately receive air and liquid during the movement of the latter and means forming passageways for air and liquid extending from said reservoirs to a level below that of the air chamber.
- 45 6. In a liquid indicating device for a tank, the combination with an air chamber within the tank and in communication with the liquid to be measured, a gauge, and a conduit connecting said air chamber and gauge, of
- 50 means for replenishing air in said air chamber, said means including a conduit extending above the level and below the level of the air chamber and adapted to communicate with the air above the liquid and having an opening beneath said air chamber, and a reservoir at the upper end of said conduit and arranged to receive liquid from the tank, said reservoir being of greater diameter than said conduit and surrounding the upper end thereof, said conduit projecting above the bottom of said reservoir, and a cap member of intermediate diameter inverted over and having its top spaced from the end of said conduit, said cap member being located within said reservoir.
- 55 In testimony whereof I affix my signature.
